REGISTERS

Philip H. Allen, Los Gatos, Calif., and Benjamin J. Chromy, Washington, D.C.

Original application January 11, 1946, Serial No. 640,464, now Patent No. 2,727,683, dated December 20, 1955. Divided and this application December 16, 1955, Serial No. 553,639.

12 Claims. (Cl. 235—92)

The present invention relates to registers and is concerned more particularly with the provisions of improved adding and calculating apparatus employing electronic devices.

This application is a division of our application Serial No. 640,464 filed January 11, 1946, now Patent No. 2,727,683, for Registers.

It is a general object of the invention to provide improved registering apparatus of ultra high speed operating characteristics.

Another general object of the invention is to provide registering apparatus including an improved register employing gaseous or other electric discharge devices in the various orders thereof.

Another object of the invention is to provide improved registering apparatus wherein thermionic discharge devices are employed in registering values.

Another object of the invention is to provide improved registering apparatus wherein light sensitive or responsive means is employed in effecting registry of values.

Another object of the invention is to provide an improved counting device employing thermionic tubes and light sensitive or responsive tubes or cells associated therewith in effecting a counting operation.

Other objects and advantages of the invention will be apparent from the following description of certain preferred embodiments thereof as illustrated in the drawings, in which:

Figure 1 is a wiring diagram of the units order of the accumulator register.

Figure 2 is similar to Figure 1 but shows the "10's" order of the register.

Figure 3 is similar to Figure 1 but illustrates a modified form of the invention.

Figure 4 is a fragmentary wiring diagram of another modification.

Figure 5 is a fragmentary wiring diagram illustrating a further modification of the register circuit; and

Figure 6 is a fragmentary wiring diagram of still another modification of an ordinal circuit.

Generally, the invention comprises electronic register apparatus in which the register or accumulator comprises ordinal sets of electric discharge devices so arranged and related that successive electrical impulses or differentially timed electrical signals applied to the various orders thereof will result in step by step registering of the pulses as increments, so that the register can be employed in adding, subtracting, multiplying and dividing operations.

The register shown in Figure 1 consists of a plurality of thermionic tubes, such as 55, 56, 57 and 58, which may be of the three-electrode or multiple-grid type with directly or indirectly heated cathodes or filaments or cold cathode type, as desired. Furthermore, these tubes are preferably of the gas discharge type provided with an evacuated envelope of glass or similar transparent or translucent material coated on the inside over at least a part of the surface with a fluorescent material, such as

2

willemite, scheelite, zinc sulphide or the like. A small amount of mercury is provided in the inside of each of these envelopes for the purpose of generating ultraviolet radiations when the respective tubes are fired or triggered

5 by suitable electrical pulses applied to the grids thereof, the aforesaid ultraviolet radiations being employed to bombard the fluorescent coatings inside of the triggered tubes and the fluorescent coatings caused to fluoresce. The fluorescent light is employed to enable the various tubes of the register as will be apparent from further paragraphs of this description and it is of course obvious that instead of this fluorescent light, the light produced by an ionized gas may be used. In this case the thermionic tubes of the registers need not be provided with fluorescent coating as described above but the envelopes thereof may simply be filled with a suitable atmosphere of inert gas, such as, neon, argon, helium, krypton, zenon or nitrogen or suitable mixtures thereof with or without a small drop of mercury after the air is evacuated from the envelopes.

The input terminals 59 and 60 are connected to the inputs of all of the tubes 55, 56, 57 and 58 so that an electric pulse from the light sensitive tubes 17 and 18 is applied through these terminals to the aforesaid input circuits. Each of the thermionic tubes 55, 56, 57 and 58 is shunted by a light sensitive tube or cell 61, 62, 63 and 64, respectively, and light sensitive tubes or cells 65, 66, 67 and 68 are connected in series with the thermionic tubes 55, 56, 57 and 58, respectively. Likewise, the glow tubes 69, 70, 71 and 72 are connected in series with the light sensitive tubes or cells 65, 66, 67 and 68, respectively. These glow tubes 69, 70, 71 and 72 may be provided with fluorescent coatings therein as described above in the cases of thermionic tubes 55, 56, 57 and 58, or they may be simply filled with an inert gas or gases so that they will either fluoresce or glow when they are energized.

The tube 58 is the "zero" tube, tube 57 is the No. 1 tube and this is followed by the No. 2, No. 3, No. 4, 40 No. 5, No. 6 and No. 7 tubes (not shown). The No. 7 tube is followed by the tube 56 which is the No. 8 tube and this is followed by tube 55 which is the No. 9 tube.

While only four thermionic tubes 55 through 58 are shown in Figure 1, it will be understood that ten such tubes representing the values "0" through "9" inclusive, are provided in each ordinal register circuit and the corresponding numbers are applied to the glow discharge tubes 69, 70, 71 and 72 so that the number corresponding to the tube firing is illuminated and displayed.

The grids of the tubes 58, 57, 56 and 55 are connected to the input terminal 60 through capacitors 158, 157, 156 and 155, respectively, and the cathodes of these tubes are all connected to the input terminal 59, the aforesaid terminals 59 and 60 being connected together by a high resistance resistor 590. Grid leak resistors 258, 257, 256 and 255 are connected between the control grids and cathodes of the tubes 58, 57, 56 and 55, respectively. Resistors 358, 357, 356 and 355 are connected across the tubes 58, 57, 56 and 55, respectively, and these resistors are shunted by the light sensitive or responsive tubes or cells 64, 63, 62 and 61, respectively.

As previously described, light sensitive tubes or cells 68, 67, 66 and 65, shunted by resistors 168, 167, 166 and 165, respectively, are connected in series with the outputs of the tubes 58, 57, 56 and 55, respectively. Glow discharge or gas tubes 72, 71, 70 and 69, shunted by resistors 172, 171, 170 and 169, respectively, are connected in series with the light sensitive tubes or cells 68, 67, 66 and 65, respectively. These glow discharge tubes 72, 71, 70 and 69 are also shunted by R-C networks consisting of resistors and capacitors connected in

series across the respective glow discharge tubes. These R-C networks function to stabilize the circuit and prevent transient impulses. Thus variable resistors 272, 271, 270 and 269 are connected in series with capacitors 372, 371, 370 and 369, respectively, and these series connected elements are in turn connected across the glow discharge tubes 72, 71, 70 and 69, respectively.

The register shown in Figure 2 constitutes the tens order of the register or totalizer and is identical with Figure 1 except for the addition of carry control elements conditioned by carry impulses from the terminals 90 and 91 of Figure 1. The Figure 2 embodiment consists of a plurality of tubes, such as tubes 55a, 56a, 57a and 58a, which are identical to the tubes 55, 56, 57 and 58 shown in the register of Figure 1. This register also includes additional tubes which are not shown, the same as the register illustrated in Figure 1, and the tubes 55a, 56a, 57a and 58a may be designated as the No. 9 tube, No. 8 tube, No. 1 tube and the "0" tube, respectively, the same as corresponding tubes in Figure 1. The same or similar circuit elements are associated with the tubes 55a, 56a, 57a and 58a, as are associated with the corresponding tubes shown in Figure 1 and like elements of Figures 1 and 2 are designated by like reference numerals except that the reference numerals employed in Figure 2 each have the letter "a" as a suffix.

The different orders 10, 110, 210, 310 and 410 of the register are provided with positive anode battery terminals 92, 92a, 92b, 92c, 92d and 92e, respectively.

Transfer circuit

The register circuit of Figure 1 is provided with a transfer circuit in the output of the No. 9 tube, that is, tube 55, for tens transfer purpose, whereby tens transfer pulses are fed to the input terminals 59a and 60a of the circuit shown in Figure 2.

This transfer circuit consists of a transformer 455 (Figure 1) having the primary thereof connected in series with the anode of the tube 55 and the tube output circuit. The secondary of the transformer 455 is connected to terminals 90 and 91. A tens transfer switch or key 855 is connected in series with the rectifier 555, the capacitor 755 and light sensitive tube or cell 955. Furthermore, the capacitor 755 is connected in series with the aforesaid light sensitive tube or cell 955 across a pair of output terminals 856 and 956, and these in turn are connected to the terminals 59a and 60a, respectively, of Figure 2.

Thus, a tens transfer pulse occasioned by the extinguishing of the No. 9 tube 55 will serve to charge the capacitor 755, the rectifier 555 serving to prevent charging of this capacitor upon initial firing of the tube 55. Subsequently, when the light sensitive cell or tube 955 is rendered conducting or active by a light ray from the selection mechanism 16 as disclosed in our Patent No. 2,727,683, the capacitor 755 will be discharged. A tens transfer pulse is accordingly fed to the input terminals 59a and 60a of Figure 2 as outlined above, whereby a tens transfer pulse may be impressed upon the output or grid circuit of any one of the register tubes 58a, 57a, 56a or 55a of Figure 2, depending upon which of these tubes is conditioned to receive the pulse.

Similarly, the No. 9 tube, that is, tube 55a of the register 110 shown in Figure 2 is provided in the output circuit thereof with a tens transfer circuit coupled to the output of this tube by means of the transformer 455a. The secondary of this transformer is connected to the terminals 90a and 91a which are connected to the transfer circuit leading to the next register order.

Resetting or "0" tube conditioning circuit

In order to effect resetting of the accumulator, means is provided to erase any values displayed in the various orders thereof by momentarily disabling all the register tubes, and for subsequently enabling the "0" tubes of

each order. At the same time, the transfer circuits are momentarily disabled to prevent false tripping of a tens transfer during the value erasing operation. Depression of the resetting control key 14 (Figure 7) results in first opening the switch 855 (Figure 2), thereby preventing false tripping of a tens transfer, and thereafter opening the switch 13 etc. for momentarily disabling all the register tubes.

The terminals 95—96 are connected to a small light and the primary of a transformer, such as the light 97 and the transformer 98 shown in Figure 1. The light 97 is positioned to energize the light sensitive cell or tube 68, as shown in Figure 1, and the secondary of the transformer 98 is connected between a second control grid and the cathode of the "0" tube 58.

When the light sensitive cell or tube 68 is energized by the light 97, the circuit of the zero tube 58 is conditioned for operation since energizing this light sensitive cell or tube greatly reduces the resistance of this cell or tube and increases the plate voltage applied to the plate of the tube 58 from a battery connected to the terminal 92 and the conductor associated therewith. At the same time as the plate voltage applied to the tube 58 is increased in this fashion, the voltage applied across 20 the glow lamp 72 is increased but not sufficiently to ionize the gas in this glow lamp. However, a positive voltage pulse is applied to the auxiliary control grid of the tube 58 with respect to the cathode of this tube from the secondary of the transformer 98 since this transformer 25 is connected to a suitable battery 15 and key 14 and this pulse fires the tube 58 thereby increasing the current through this tube sufficiently to ignite or ionize the gas of the glow lamp 72. Ionization of the glow lamp 72 illuminates the character "0" associated therewith. Accordingly, the "0" tube 58 and associated glow lamp 72 of the register 10 and corresponding "0" tubes and associated glow lamps in each of a plurality of registers are conditioned for operation when a voltage is applied to the terminals 95 and 96 and the glow lamps associated with the "0" tubes cause each of the registers to indicate zeros.

Register operation

With the "0" tube of the ordinal circuits in firing condition, an impulse fed to the input terminals 59—60 of the register 10, for example, will fire the No. 1 tube 57 since the light from the ignited "0" tube 58, being directed to the light sensitive tube or cell 67, connected in series with this tube 57, has conditioned the plate circuit of this tube for firing of the tube. The electric pulse applied between the grid and cathode of the tube 57 therefore renders this tube conductive or substantially increases its conductivity and the increased plate current ionizes the glow tube 71 which is associated with the character "1" of the register 10 and illuminates this character. Simultaneously the light from the ionized gas of the tube 57 or the light from the fluorescent coating provided in this tube, is directed to the quenching light sensitive tube or cell 64, connected from the plate to the cathode of the "0" tube 58. This quenching tube or cell 64 and other similar tubes or cells 63, 62 and 61 in the register 10 and similar tubes or cells in registers 110, 210, 310, 410 and 510 may be resistance type light responsive cells adapted to decrease in resistance by a substantial factor when illuminated or they may be gas type light sensitive tubes the gases in which are ionized by the potentials across them when the tubes are illuminated. Therefore, when the quenching cell or tube 64 is illuminated it functions because of its greatly lowered resistance to shunt the thermionic tube 58 and bleed off the current flowing through the tube 58 with the result that the tube 58 does not receive sufficient current to maintain its ionized condition and is quenched.

As described above, the glow discharge from the tube 58 illuminates the light sensitive tube or cell 67 and 75 primes the thermionic tube 57 so that a pulse applied to

the terminals 59 and 60 is received by the "1" tube 57 and fires or renders this tube conductive. The light from the glow discharge of this tube 57 is received by the quenching tube or cell 64 of the thermionic tube 58 so that the latter tube is quenched. Light from the tube 57 is also received by the light sensitive tube or cell which primes the No. 2 tube (not shown) connected to this tube in the same manner as the light sensitive cell or tube 67 is connected to the No. 1 tube 57. Likewise, when a second pulse energizes the No. 2 tube the glow discharge from this tube energizes the light sensitive quenching tube or cell 63 which functions as a quenching circuit for the tube 57 and also primes the circuit of the No. 3 tube so that the third pulse received by the input circuit is applied to the input of the No. 3 thermionic tube. Successive pulses applied to the input terminals 59 and 60 will cause the No. 4, No. 5, No. 6, No. 7, No. 8 and No. 9 tubes to fire or become conductive successively and the light from the No. 4 tube functions to quench the No. 3, that from the No. 5 tube quenches the No. 4 tube, the light from the No. 6 tube quenches the No. 5 tube, the light from the No. 7 tube quenches the No. 6 tube, the light from the No. 8 tube 56 quenches the No. 7 tube, and the light from the No. 9 tube 55 falls on the cell or tube 62 to quench the tube 56 and the light from the No. 9 tube 55 also falls on the tube or cell 68 of the "0" tube 58 to enable this "0" tube for reception of the next pulse applied to the terminals 59 and 60.

Operation of transfer circuit

The transfer circuit 11 connected through terminals 93 and 14 to the terminals 90 and 91 of the register 10 functions when the No. 9 tube 55 is quenched as a result of the input circuit of the register 10 receiving a tenth pulse, to apply a pulse to the input circuit of the next higher order register 110. The transfer circuit 11 receives the pulse from the transformer 455 and stores this pulse in the capacitor 755 for application to the input of the next higher order register 110. The rectifier 555 is connected in such manner that only the decaying current in the primary of the transformer 455 induces an E.M.F. into the secondary of this transformer of the proper polarity to pass a current through the rectifier 555 and charge the capacitor 755. Thus this capacitor 755 is charged when the No. 9 tube 55 is quenched, that is, when the current through the primary of the transformer 455 decays. However, if the No. 9 tube 55 is energized when the resetting key 14 is operated to recondition the circuit or set it to zero no transfer impulse will be stored because the switch 855 is opened to disable the transfer circuit before the switch 13 is opened so that the capacitor 755 is not charged at this time.

Register in which separate glow tubes are eliminated

With the provision of fluorescent coatings inside of the register thyratrons or thermionic devices 55, 56, 57 and 58 of Figure 1, 55a, 56a, 57a and 58a of Figure 2, etc., it is apparent that the function of illumination of the legends, numerals and the like associated with the glow lamps 69, 70, 71 and 72 of Figure 1 and 69a, 70a, 71a and 72a of Figure 2, respectively, may be performed by the register thyratrons or thermionic devices 55, 56, 57 and 58 of Figure 1 and 55a, 56a, 57a and 58a of Figure 2, respectively, since sufficient light will be given off by these thyratrons for such illumination. These glow lamps 69, 70, 71 and 72 of Figure 1 and 69a, 70a, 71a and 72a of Figure 2 together with the resistors 269, 269a, 270, 270a, 271, 271a, 272 and 272a and capacitors 369, 369a, 370, 370a, 371, 371a, 372 and 372a of Figures 1 and 2 may therefore be eliminated if desired. The plate current supplies for the thyratrons in these figures may be connected by shorting the glow lamps, that is, by removing the glow lamps completely and connecting the thyatron plate current supply directly to the anodes of the enabling light responsive devices 65, 65a, 66, 66a, 67,

67a, 68 and 68a of Figures 1 and 2. The circuit diagram for an ordinal portion of the register of a reversible character is shown in Figure 3 which is similar in all respects to the circuit of Figure 4 with the exception that provision is made for transferred increments or pulses during both negative and positive operation. A register of reversible character as referred to is fully disclosed in our Patent No. 2,727,683.

It will be recalled in connection with the circuit shown in Figure 1 that the transfer signals or pulses from one order of the register to the next order are obtained from the decay of the current through the No. 9 tube 55b, through the transformer 455b. Similarly, for negative transfer signals or pulses, a transformer 99b is incorporated in the plate circuit of the No. 0 tube 58b to provide a transfer pulse upon decay of this circuit. Both the transformers 455b and 99b are connected in parallel to the output terminals 90b and 91b with the provision of respective control switches 88b and 89b, respectively, to enable the desired transfer circuit in accordance with the character of the operation being performed. For example, when the register is set for addition, the switch 88b is closed and the switch 89b is open, so that only additive transfer pulses will be transmitted to the next higher order register circuit. Conversely, in subtraction, the switch 89b is closed and the switch 88b is open so that only subtractive transfer pulses will be permitted during the subtracting operation.

Modified register circuits

The register 10 consisting of the tubes 55, 56, 57 and 58 may be connected as shown in Figure 1, however, modified circuit diagrams such as shown in Figures 4, 5 and 6 may be employed if desired and in each of these figures the elements having functions corresponding to the elements shown in Figure 1 are designated by corresponding reference numerals except that in Figure 4 the reference numerals are provided with a suffix "c," and in Figure 5, the elements are provided with the suffix "d," and in Figure 6, they are provided with a suffix "e." In Figure 4, two tubes 58 and 57 of the thyatron tube corresponding to tubes 58 and 57 of Figure 1 are shown, whereas in Figure 5 only one tube 58d corresponding to tube 58 in Figure 1, and in Figure 6 one tube 58e likewise corresponding to tube 58 of Figure 1, are shown.

Referring to Figure 4 in detail, light responsive device 68c is energized by a suitable light source in a manner previously described in the description of corresponding light sensitive devices in Figures 1, 2 and 3, and the impedance of this light responsive device 68c is decreased so that the current through this device, the resistors 172c and 272c and the device 58c is increased. The potential drops across these resistors are therefore increased and the charge of the capacitor 372c is also increased. The circuit of the thyatron or gas discharge tube 58c is thus enabled since the plate potential of this tube is increased. A positive electrical pulse or wave applied to the grid of the tube 58c fires or triggers this tube and causes the potential across this tube to ionize the gas and the small quantity of mercury therein so that the fluorescent coating therein is energized and the fluorescent light therefrom illuminates another light responsive device such as device 67c for enabling the circuit of another thyatron 57c. At the same time the fluorescent light from the thyatron 58c illuminates a quenching cell corresponding to cell 64c for quenching or extinguishing another thyatron that was energized prior to the energization of thyatron 58c. With the firing of the thyatron 58c the impedance thereof decreased so that the current therethrough increased and accordingly the current through the light responsive device 68c increased since the potential thereacross increased. However, the same pulse as was used to trigger the thyatron 58c also triggered the gas glow tube 72c since the trigger electrode thereof is connected to the grid of the

thyatron through the current limiting resistor 72x. The glow tube 72c is thus energized and caused to glow by the discharge of the capacitor 372c therethrough and by some of the current flowing through the thyatron 58c. The glow tube 72c thereby illuminates the numeral character or other legend associated therewith.

The light from the ionized gas or energized fluorescent coating in the thyatron 58c enables the circuit of another thyatron 57c by illuminating the light responsive device 67c so that the next electrical pulse or wave applied to the input grid-cathode circuit of the thyatrons triggers this thyatron 57c and the light from the ionized gas or energized fluorescent coating in this latter thyatron illuminates the enabling light responsive device of the third thyatron and the light responsive quenching device 64c associated with thyatron 58c. The light responsive quenching device 64c bleeds off the current from the light responsive device 68c and the thyatron 58c thereby quenching the ionization in these devices.

In the apparatus shown in Figure 5, the tube 58d of the thyatron type is provided with five electrodes, namely, a cathode, a control grid, a second control grid, an anode and a cutoff grid positioned between the anode and the second control grid. The anode of the tube 58d is connected to one terminal of the light sensitive enabling device 68d and the other terminal of this light sensitive device is connected to one terminal of the glow lamp 72d. The other terminal of the glow lamp 72d is connected to the positive busbar which is connected to the terminal 92d. The control grid of the tube 58d is connected to the signal input line coupling capacitor 158d and to the grid resistor 258d. The auxiliary control grid of the tube 58d is connected to the secondary of the transformer 98d, the primary of this transformer being connected to the terminals 95 and 96. A small lamp 97d for energizing the light sensitive device 68d is also connected to the terminals 95 and 96.

The operation of this register arrangement is similar to that of the register arrangement shown in Figure 1. However, in this case the quenching or cutoff light sensitive device 64d is connected in series with the entire voltage divider consisting of the series-connected resistors 172d, 168d and 358d which are connected between the positive busbar and the cutoff grid of the tube 58d. The cutoff grid of the tube 58d is connected to one terminal of the light sensitive device 64d and the other terminal of this device is connected to the cathode busbar. The resistor 172d is also connected across the glow lamp 72d; resistor 168d is connected across the light sensitive device 68d and resistor 358d is connected between the anode and cutoff grid of the tube 58d. Consequently, when the light sensitive device 64d is energized for quenching or cutoff purposes, the potential on the cutoff grid of the tube 58d is substantially reduced so that the ionization of the gas inside of the tube 58d is quenched. The impedance of this tube, therefore, increases immediately after the quenching device 64d is energized and as a result the gas in the tube 72d is also deionized.

The function of the device 72d is the same as the function of the device 72 in Figure 4 and as previously described these functions may be combined into the function of the thyatron 58d, particularly where this thyatron is provided with a fluorescent coating therein as described above.

In Figure 6 the thyatron tube 58e which corresponds to the thyatron tube 58 in Figure 1 is provided with a cutoff electrode between the cathode and the control grid and this cutoff electrode is connected to the anode through the light sensitive quenching device 64e. In this case when the light sensitive device 64e is energized the space between the cutoff electrode and the anode is shunted by a low impedance path of the energized device 64e, and in this manner, the tube 58e is deionized.

The modified form of this register shown in Figure 6

also shows the register circuit in which the glow lamp corresponding to the glow lamp 72 has been eliminated and in this case the resistor 168e corresponding to the resistors 168 and 172 of Figure 4 is connected to the positive busbar. The light sensitive enabling device 68e corresponding to the device 68 of Figure 4 is connected between a variable contactor associated with the resistor 68e and one of the terminals thereof. This circuit illustrates the manner in which the components may be connected when the glow lamps corresponding to glow lamp 72 of Figure 1 are eliminated. Likewise, in Figures 4 and 5 the glow lamps 72c and 72d, respectively, may be eliminated and the function thereof incorporated in the functions of the tubes 58c and 58d. From the above description it will be seen that the light from a fired gaseous discharge tube will illuminate effectively the priming phototube for the next digital value and also the quenching phototube for the previously fired tube in the original series of tubes.

We claim:

1. Electrical register and computing apparatus comprising an electrical device having a group of electric discharge paths, said paths being designated as the "0," "1" and "2" paths, each of said paths including an electric discharge device having an anode and a cathode, a light sensitive device connected in series with each said electric discharge device, a second light sensitive device connected across at least a part of the discharge path of each of said electric discharge devices, a common circuit for applying electric pulses to all of said electric discharge devices, means for firing the electric discharge device of the "0" path, said last mentioned device being adapted to produce luminous radiation to energize the light sensitive device connected in series with the electric discharge device of the "1" path so as to condition this discharge device path for firing upon the receipt of the next electric pulse by said common circuit whereby the discharge device of said "1" path is selectively fired by the said next pulse, the discharge device of said "1" path when fired producing luminous radiation for energizing the light sensitive device connected across the electric discharge device of the "0" path to quench the firing of this device, the luminous radiation produced by the discharge device of said "1" path also energizing the light sensitive device connected in series with the electric discharge device of the "2" path so as to condition this path for firing by the second pulse received by said common circuit, the electric discharge device of the "0" path having a reset electrode and means connected to said reset electrode for resetting the apparatus.

2. Apparatus as set forth in claim 1 further comprising resistance elements connected across said light sensitive devices.

3. Apparatus as set forth in claim 2 further comprising gas discharge devices connected in series with each of the electric discharge devices, each of said gas discharge devices having a number associated therewith and said number being adapted to be illuminated when the corresponding gas discharge device is fired.

4. Apparatus as set forth in claim 3 further characterized in that said gas discharge device includes a firing electrode and means for connecting said firing electrode to said common circuit.

5. Apparatus as set forth in claim 1 further characterized in that said electric discharge devices are each provided with a cutoff electrode and means for connecting said second light sensitive device associated with each of said electric discharge devices between the cutoff electrode and another electrode of the associated electric discharge device.

6. Apparatus as set forth in claim 5 further characterized in that said other electrode is the cathode of the respective electric discharge devices.

7. Apparatus as set forth in claim 5 in which said

other electrode is the anode of the respective electric discharge device in each case.

8. Apparatus as set forth in claim 7 further comprising a variable resistance connected across each of the light sensitive devices that are connected in series with the anodes of each of the electric discharge devices.

9. In an electronic calculating apparatus, a plurality of electric discharge devices, connections for connecting said electric discharge devices into a series having means for firing said devices in sequence to place a value therein, a gas indicator tube for each of said electric discharge devices, each indicator tube having a triggering electrode, each triggering electrode being connected to the means for firing said devices in sequence, whereby said gas indicator tubes are fired in the same sequence, means for removing any value standing in said series, means for resetting said series, said last mentioned means including an auxiliary grid electrode in one of said devices.

10. In an electronic calculating apparatus, a plurality of electric discharge devices, connections for connecting said electric discharge devices into a series having means for firing said devices in sequence, a gas indicator tube for each of said electric discharge devices, each indicator tube having a triggering electrode, each triggering electrode being connected to the means for firing said devices in sequence, whereby said gas indicator tubes are fired in the same sequence, means for resetting said series, said last mentioned means including an auxiliary grid electrode and means for energizing said electrode to reset the apparatus.

11. In an electronic calculating apparatus, a plurality of electric discharge devices, connections for connecting said electric discharge devices into a series having means for firing said devices in sequence, a gas indicator tube for each of said electric discharge devices, each indicator tube having a triggering electrode, each triggering electrode being connected to the means for firing said devices in sequence, whereby said gas indicator tubes are

fired in the same sequence, one of said devices having means for resetting said series, said last mentioned means including a resetting electrode, and means for energizing said electrode to reset the apparatus.

- 5 12. In an electronic calculating apparatus, a plurality of electric discharge devices, connections for connecting said electric discharge devices into a series in which said devices are designated as the "0" and "1" devices, said devices having means for the firing thereof in sequence, 10 a gas indicator tube for each of said electric discharge devices, each indicator tube having a triggering electrode, each triggering electrode being connected to the means for firing said devices in sequence, whereby said gas indicator tubes are fired in the same sequence, said device 15 designated as the "0" device having an auxiliary grid electrode.
